(57) **CLAIM**

The ornamental design for an earring, as shown and
described.

DESCRIPTION

FIG. 1 is a perspective view taken from the top and left side
of an earring showing my new design;

FIG. 2 is a front view thereof;

FIG. 3 is a rear view thereof;

FIG. 4 is a top view thereof;

FIG. 5 is a bottom view thereof;

FIG. 6 is a right side view thereof; and,

FIG. 7 is a left side view thereof.

All elements of the photographs not directly attached or
affixed to the earring depicted in FIGS. 1-4, including
reflections, shadows, and holding fixtures attached to the
bottom of the earring are disclaimed and form no part of the
claimed design.
